CLAIM

The ornamental design for a cane tip, as shown and described.

DESCRIPTION

FIG. 1 is a perspective view of a cane tip showing my new design;

FIG. 2 is a Front view of the cane tip as shown in FIG. 1;
 FIG. 3 is a Back view of the cane tip as shown in FIG. 1;
 FIG. 4 is a Left-side view of the cane tip as shown in FIG. 1;

FIG. 5 is a Right-side view of the cane tip as shown in FIG. 1;

FIG. 6 is a Top view of the cane tip as shown in FIG. 1; and,
 FIG. 7 is a Bottom view of the cane tip as shown in FIG. 1.
 The broken lines depict portion of the article that form no part of the claimed design.

1 Claim, 7 Drawing Sheets
